UNITED STATES PATENT OFFICE.

LLEWELLYN P. DAVIS, OF CHICAGO, ILLINOIS, ASSIGNOR TO THE AMERICAN WOOD DECORATING MACHINE COMPANY, OF NEW YORK, N. Y.

ADJUSTABLE WORK-SUPPORT.

SPECIFICATION forming part of Letters Patent No. 530,258, dated December 4, 1894.

Application filed October 16, 1893. Serial No. 488,246. (No model.)

To all whom it may concern:

Be it known that I, LLEWELLYN P. DAVIS, of Chicago, in the county of Cook and State of Illinois, have invented certain new and useful Improvements in Adjustable Work-Supports; and I do hereby declare that the following is a full, clear, and exact description thereof, reference being had to the accompanying drawings, and to the letters of reference marked thereon, which form a part of this specification.

The object of this invention is to provide an improved construction in work-supporting devices to be employed in connection with wood embossing or decorating machines, such as are used for ornamenting wood moldings and the like. The invention consists essentially in a traveling work support, adapted to be adjusted in such manner as to bring an inclined surface of the molding or other strip to be decorated into a horizontal position to meet the working face of the die or embossing roller, which latter, in connection with my improvement, always preserves a horizontal axis of rotation. Heretofore machines of this character have been adapted to produce the same general result by adjustment of the die or embossing roller to the required angle, but such construction has many and serious objections, all of which are obviated by my present improvement.

The nature of the invention will be understood from the following description of the accompanying drawings, in which—

Figure 1 is a side elevation of parts of two adjacent sections of the work support embodying my invention. Fig. 2 is a transverse vertical section taken on line 2—2 of Fig. 1, showing the arrangement of the clamp which holds the parts of a section in adjusted relation; also the supporting bed roll upon which the work support travels and parts of the main supporting table, shown in section. Fig. 3 is a plan view of the lower part or shoe of a section and the part of the clamping mechanism carried thereby, the upper part of the support being removed.

As shown in said drawings, A designates the traveling work support as a whole; B, the main table of the machine; C, the bed roll upon which the work support is carried; D,

the usual die or embossing roller of the machine, and E a piece of molding being carried by the work support and acted upon by the roller D. The die D may be understood as being held by an arm arranged above the bed or supporting table B and the material as being carried over the table beneath said die by means of a driven bed roll in the usual manner.

The work support A is composed of two principal parts A' and A², the lower portion A' having a flat under surface and straight parallel sides. In practice it will usually be made in sections or lengths of about three feet or of other length convenient for handling. The upper surface of the lower portion A' is provided with a longitudinal cavity a, the surface of which is a part of a cylinder, and to this is accurately fitted the lower surface of the superposed part A². The upper surface of the part A² is composed of three surfaces which in this instance are planes, two of which, to wit: a' and a³, are parallel and the third, a², intersects them to form a shoulder against which one edge of the molding strip E may bear while its bottom rests upon the lower surface a'. The surfaces a' and a³ are desirably protected by a sheet metal facing, as indicated in Fig. 2. Obviously the upper part A², having its lower surface convex, may be rotated in the cavity a of the lower part A' so as to bring the upper inclined surface of a molding placed upon the part A² into a horizontal position so that said upper surface may fairly meet the peripheral surface of the embossing die or roller D, as indicated in Fig. 2, and this will be true no matter what the inclination of the upper surface of said molding may be to the lower surface which rests upon the support.

Means are desirably provided for holding the upper part A² firmly to the lower part A' of the work-support at any angle or other position to which said upper part may be brought. Such means, as shown in the drawings, consist of a clamping bolt G having a head g upon its lower end and a nut g' upon its upper end; said bolt passing through the upper part A² of the work support. The head g of said clamping bolt engages beneath flanges f² of a T-groove F' formed in a curved

metal block F which is secured transversely to the part A'. Preferably said T-grooved metal block F has its margins f flush with the concave surface a of said part A' of the support, and has a central elevated portion f' containing the T-groove F', which elevated part f' fits a transverse groove a' in the lower convex surface of the upper part A². As shown, the head g of the clamping bolt G is cut away on its sides to conform to the lower convex surfaces of said flanges f² which border the T-groove F' so that said head bears broadly against said surfaces and is adapted to hold firmly without slipping. It will be observed that the clamping bolt G is arranged to protrude through the more elevated surface a² of the upper part A² of the support where it is at all times accessible and permits of the clamp being tightened after the adjustment has been effected beneath the pressure of the roller die D.

Other forms of means for clamping the parts or for holding them in the selected relation may be adopted in place of the clamping bolt and T-grooved part F herein shown without departure from my invention.

The upper part A² of the work support will ordinarily be of the same length as the lower part A', but desirably said upper part will be placed so as to overhang the lower part at one end and to leave the lower part projecting beyond the upper part a corresponding distance at the other end. By this construction two supports, when placed end to end, will overlap, as indicated in Fig. 1, and they will better support the work beneath the pressure of the roller die as the joint between two sections passes over the subjacent bed roller C.

I claim as my invention—

1. An adjustable, traveling work support comprising a base member for engagement with the feed roller of a wood decorating machine or the like, a work supporting member

resting upon said base member and adapted for angular adjustment with relation to the latter, and securing devices for retaining said member in adjusted relation, substantially as set forth.

2. An adjustable, traveling work support comprising a base member for engagement with the feed roller of a wood decorating machine or the like, a work supporting member superimposed upon said base member, the meeting faces of said members being respectively concave and convex in cross section, and devices for securing said members together in adjusted angular relation, substantially as set forth.

3. A system of traveling work supports for wood decorating machines, comprising a series of sections or lengths each composed of a lower part and an upper part, the latter of which has its upper surface adjustable to any desired angle, as set forth, the upper and lower parts being of equal length but placed in overhanging relation to each other, whereby the several sections of the system will overlap each other when placed end to end in the machine, substantially as described.

4. In combination with the lower part A' of the traveling work support having its upper surface concave in cross-section and provided with a curved metal part F having a T-groove therein extending transversely of the support, the upper part A² of the support having a lower surface fitted to the concaved upper surface of said lower part A' and provided with a clamping bolt G engaged with the said T-groove, substantially as described.

In testimony that I claim the foregoing as my invention I affix my signature in presence of two witnesses.

LLEWELLYN P. DAVIS.
